(57) **CLAIM**

The ornamental design for the carrying handle for batteries, as shown and described.

DESCRIPTION

FIG. 1 is a front perspective view of a carrying handle for batteries incorporating my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left end view thereof; and,

FIG. 8 is a front perspective view thereof engaged with a battery.

The dashed lines in FIGS. 1-8 are for illustrative purposes only and form no part of the claimed invention.
